UNITED STATES PATENT OFFICE.

PHILIP D. JOHNSON, OF CHICAGO, ILLINOIS, ASSIGNOR OF ONE-HALF TO CHARLES A. BROWN, OF HINSDALE, ILLINOIS.

BURNER.

1,300,171.

Specification of Letters Patent.

Patented Apr. 8, 1919.

Application filed December 18, 1916. Serial No. 137,492.

To all whom it may concern:

Be it known that I, PHILIP D. JOHNSON, a citizen of the United States, residing at Chicago, in the county of Cook and State of Illinois, have invented a certain new and useful Improvement in Burners, of which the following is a full, clear, concise, and exact description, reference being had to the accompanying drawings, forming a part of 10 this specification.

My invention relates to oil burners.

It is to be understood that certain of the features of this invention are applicable to gas burners and burners for other types of 15 fuel as well.

In burning liquid fuel it is difficult to vary the total amount of fire over a large range although such result is highly desirable in the interest of convenience, economy and efficiency.

My invention provides an improved burner construction which makes possible variation of the size of the fire over a wide range under economical and efficient conditions.

25 The invention will be better understood by reference to the accompanying specification and drawings in which I have described and illustrated a particular embodiment of the invention. In the drawings—

30 Figure 1 is a top plan view of a burner embodying my invention;

Fig. 2 is a left side elevation with parts broken away;

Fig. 3 is a fragmentary section taken on 35 the lines 3, 3 of Fig. 2;

Fig. 4 is a front elevation of the burner shown in Figs. 1 and 2 with a part broken away to reveal the interior;

Fig. 5 is a rear elevation of the same;

40 Fig. 6 is a front elevation of a modified form of burner which is embodied in a tinner's furnace;

Fig. 7 is a transverse cross-section of the same; and

45 Fig. 8 is a longitudinal cross-section of the central burner showing the arrangement of mixing and distributing tubes.

In the device which I am about to describe I wish to call attention to the two co-operating mechanisms which are provided for varying the size of the fire. I provide first a valve and co-operating means governing the extent or distribution of active burner area, and second a valve and co-operating means for determining the amount of 55

fuel supplied and for properly distributing the same.

The device which I have illustrated comprises essentially oil supplying and vaporizing means, vapor mixing and distributing 60 means and burner screens for burning the mixture. My invention resides in the novel arrangement and co-operation between these various elements and in the organization of certain of the individual elements above 65 named. The burner screen is divided into three sections, the central section 1 and outer symmetrical sections 2 and 3 arranged upon opposite sides of the main burner screen. The main burner screen 1 is formed 70 with a plurality of parallel slots 4 cut transversely on the ridge of an inverted trough-shaped casting 5 the bottom of which is closed by another trough-shaped casting 6, these two parts forming a body of 75 hollow diamond shaped section, the front end of which is connected to and mounted upon the housing 7 which will be described later. The burner 1 is provided with wings 8 and 9 which project into the housing 7 80 for a purpose later to be described. The two trough-shaped castings 5 and 6 are bolted together at the front end by flanges 10 and 12 upon the upper and lower members respectively and at the rear are bolted 85 together by means of flanges 11 and 13 upon the upper and lower members respectively. At the rear of the burner the hollow casing formed by these two members which I term hereafter the "mixing chamber" or "casing", 90 is connected to a bracket 14 which is formed as a casting with cored passageways. The casting 14 is provided with a central boss 15 in which is mounted a valve 16, later to be described. The casting 14 also comprises 95 arms 17 and 18 extending from each side at a slight angle to the horizontal. These arms have connected to them tubes 19 and 20 which pass into the hollow mixing chambers 21 and 22 respectively which have the 100 burner screens 2 and 3 in their surfaces respectively. The connecting tubes 19 and 20 communicate through suitable passageways 26—27 in the arms 17 and 18 and through the valve 16 with the main mixing 105 chamber at the center. The outer ends of the tubes 19 and 20 are closed off by suitable plugs and within the mixing chambers 21 and 22 these tubes are perforated at their lower side as is well understood in the art. 110

The casting 14 is provided with a leg 23 which supports the rear end of the device. A lug 24 formed on the casting 14 provides a support for the rear end of the vaporizer 5 as will be described later. The main mixing chamber formed by the parts 5 and 6 contains a central mixing tube 25 which extends completely through the main mixing chamber.

10 The rear end of the mixing tube 25 projects through the rear wall of the mixing chamber and opens into the hollow boss 15. The passageways 26 and 27 which communicate with the mixing tubes 19 and 20, respectively, of the supplemental burner screens communicate with the interior of the hollow boss 15. The valve member 16 is formed of a tubular portion, part of which is cut away, in order to permit the 15 passageways 26 and 27 to be opened simultaneously or to be shut off simultaneously or to be shut off individually. The valve 16 is connected by means of a stem 28 to a handle 29. A suitable stuffing box 30 may 20 be provided for maintaining the valve tight. This stuffing box is closed by a gland 31 which embraces the stem 28 of the valve. A suitable indication may be made upon the hollow boss 15 and upon the handle 29 25 to indicate when the various burner portions are connected or disconnected.

The main mixing chamber formed of the parts 5 and 6 is supplied with combustible mixture through the openings 33 which are 30 formed in the upper walls of the mixing tube 25. This mixing tube 25 is surrounded by a second mixing tube 34 which has its lower side walls perforated by the openings 35. The rear end of the mixing tube 40 25 is raised slightly above its front end so that any liquid which may be carried into the mixing tube 25 will tend to flow out at the front end thereof. The bottom walls of the tube 25 are imperforate so that 45 any oil which may be discharged into this mixing tube 25 by the nozzle 36 or otherwise will not enter the burner but will be trapped and will flow out of the front end of this tube. The nozzle 36 is provided 50 with a suitable valve 37 for controlling the rate of fuel vapor discharged into the mixing tube 25.

The nozzle 36 is supplied with oil vapor from a suitable vaporizer which is supported 55 over the main portion of the burner and is provided with oil through the elbow connection 38 which is connected by suitable piping through a tank containing oil under pressure. The vaporizer comprises an upper 60 vaporizing tube 39 and a lower vaporizing tube 40 these tubes being connected together at their rear end by a connecting block 41 which is provided with suitable cleaning openings closed by the screws 42 and 43.

65 The screw 43 which is axially in line with

the pipe 40 projects through an aperture in the lug 24, as is shown in Fig. 5, and supports the rear end of the vaporizer.

A connecting block 44 supports the upper pipe 39 which passes loosely through this 70 block and is connected to the lower vaporizing pipe 40 and has a passage therein connecting this pipe 40 with the nozzle 36. A suitable cleaning screw 45 closes a cleaning opening in line with the pipe 40. The cross 75 section of the block between the pipe 39 and the connection of the tube 40 may be diminished as by holes to prevent the transfer of heat from the lower portion of the block to the upper portion thereof. The lower portion 80 of the block is provided with shoulders 46 and 47 which project over the wings 8 and 9 of the main burner screen and form means for transferring heat from the burner to this portion of the passage through which 85 the vapor is conducted. Projecting pins 48, shown in dotted line in Fig. 4, also serve to convey heat to this part of the block. The block 44 is provided with a stud 49 which passes through the top of the casing 7 and 90 is fastened by a suitable nut 50 as shown in Fig. 2. The front part of the casing 7 is provided with a sight aperture 51 through which the condition of the fire may be observed. This aperture is normally closed 95 by a flap or door 52 which is hinged upon the front end of the pipe 39. The casing 7 is provided with a pair of supporting legs 53 and 54.

In the embodiment shown in Figs. 6 and 100 7, the burner has been adapted for use in a tinner's furnace. To this end a suitable casing 55 has been provided, this casing having suitable openings 56 and 57 through the front and back thereof in order that soldering irons may be introduced into the furnace as desired. The vaporizer in this form of the invention comprises a pair of pipes 39' and 40' which are connected at the rear by a suitable connecting block 41' this block 105 being turned so as to permit the pipe 39' to lie at a lower position than the pipe 40' and to occupy a position substantially between the main portion of the burner and the mixing chamber 21. The front connecting block 44' supports the outer end of the vaporizer pipe 39' and forms a communication between the nozzle 36 and the outer 110 end of the vaporizing pipe 40' in a manner similar to that shown in Figs. 1 to 5, inclusive. Otherwise the structure of this modification is substantially the same as that 115 shown in Figs. 1 to 5, inclusive.

The operation of the structure shown in Figs. 1 to 5 is as follows: Oil is introduced 125 under pressure at 38 and flows into the pipe 39, thence down through the connecting block 41 to the vaporizing pipe 40, where it is vaporized, and then into the nozzle 36 where the vapor is discharged into the inner 130

mixing tube 25 drawing air in with it to form a combustible mixture. If the supplemental burners are to be operated the valve 16 is suitably set to admit combustible mixture to one or the other or to both of these burners. The combustible mixture passes out of the mixing tube 25 at the rear end thereof for supplying the supplemental burner and the mixture for combustion at 10 the main burner passes out through the openings 33 in the top of the mixing tube 25 and passes into the second mixing tube 34 and thence down through the openings 35 in the bottom of the tube 34. Where only a small fire is desired the valve 37 is operated to reduce the amount of fuel vapor supplied to the mixing tube 25 and the valve 16 at the rear of the burner is set so as to disconnect the supplemental burners 2 and 3. If a greater amount of fire is desired the valve 37 is set or adjusted to admit a greater amount of oil vapor so that the fire will burn high at the main burner. Forcing of the fire at the main burner does not cause 20 uneven distribution of the burning mixture inasmuch as the two concentric mixing tubes 34 and 25 serve to equalize the pressure throughout the main burner and a uniform and even flame is secured. If a greater amount of flame is desired than can be supplied by the main burner alone one of the supplemental burners is brought into play by means of suitable setting of the valve 16. The amount of fuel mixture supplied 30 to these two burners may be regulated at the valve 37 and when a maximum of fire is desired the other supplemental burner is brought into action.

This arrangement of burners is particularly advantageous for use in the tinner's furnace shown in Figs. 6 and 7.

As previously explained the arrangement of the two concentric mixing tubes 25 and 34 is particularly advantageous in that it permits the oil which may be squirted in raw condition into the mixing tube 25 to be caused to flow out of the same because of its inclined position and due to the fact that the lower portion of the tube is imperforated. This has not been possible in burners constructed according to the prior art inasmuch as the lower part of the mixing tube has been perforated and as a result the raw oil would drip through these perforations and be trapped in the bottom of the burner casting or secondary tube, where it would vaporize irregularly.

While I have described my invention with reference to the details of the particular embodiment, it is to be understood that these details except as they appear in the appended claims may be varied within the scope of my invention. The invention does not reside in the dimensions and proportions 60 that I have shown.

I claim:

1. In combination a main burner, a pair of supplementary burners one on each side of said main burner, a mixing tube for said main burner, a bracket for supporting the rear end of said main burner and the rear ends of said supplemental burners, said supporting means having passages therein for connecting said mixing tube with said supplemental burners, and a valve controlling 75 said passages.

2. In combination, a main burner having a mixing chamber, a mixing tube projecting through said chamber, a pair of supplementary burners, means connecting said supplementary burners and said main burner, said means having passageways therethrough for connecting said supplementary burners with said main burner, and a valve controlling the passage of fuel mixture from 80 said mixing tube to said supplementary burners, said valve being operable to admit fuel mixture to either of said supplementary burners or to both of the same.

3. In combination, a main burner having 90 a relatively long narrow mixing chamber, a mixing tube extending longitudinally through said mixing chamber, a pair of supplementary burners secured beside said main burner, means for connecting one end of the 95 mixing tube of said main burner with said supplemental burners, valve means for shutting said supplemental burners and means for supplying a variable amount of fuel to the other end of said mixing tube. 100

4. In combination, a main burner, a supplemental burner, a mixing chamber for said main burner, a mixing tube in said mixing chamber, connecting means for connecting said supplemental burner with the mixing 105 tube in said main burner, a valve for said connecting means, means for supplying fuel to said mixing tube, valve means for governing the amount of fuel so admitted, and means for equalizing the distribution of 110 mixture in said main mixing chamber, said means comprising a tube concentric with said mixing tube, said tube and said mixing tube having perforations in their side walls, said perforations being out of register with 115 each other.

5. In combination, a main burner comprising a relatively long narrow burner casting, a supplemental burner extending parallel to said main burner, a mixing tube 120 in said main burner, connecting means for connecting one end of said mixing tube with said supplemental burner a valve controlling said connecting means, means for supplying fuel to the other end of said mixing tube 125 and valve means governing said fuel supply means.

6. In an oil burner, a burner comprising a mixing chamber, a mixing tube in said chamber, said tube having perforations in 130

the walls thereof, said perforations being in the upper part of the side walls of said tube, the lower side walls of said mixing tube being imperforate, said mixing tube having an opening in the end thereof whereby accumulations of oil therein will be discharged outside of said burner, and a tube surrounding said mixing tube, said second tube having perforations in the lower side walls thereof.

7. In a burner, a mixing chamber, a mixing tube in said chamber, said tube having openings in the side walls thereof, said openings pointing upward, the lower side walls of said mixing tube being imperforate, said mixing tube having an opening in the end thereof whereby accumulations of oil therein will be discharged outside of said burner, a second tube surrounding said mixing tube, said second tube having perforations in the side walls thereof, said perforations pointing downward and means for discharging a jet of fuel in said mixing tube.

8. In combination a mixing chamber, a mixing tube in said chamber, said tube having perforations in the side walls thereof pointing upward, the lower side walls of said mixing tube being imperforate, the end of said mixing tube being open, whereby accumulations of oil in said mixing tube will be discharged outside of said burner, a tube surrounding said mixing tube, said second tube having perforations in the side

walls thereof pointing downward and means for supplying oil vapor directly into the end 35 of said mixing tube, said mixing tube being inclined downward toward the open end thereof.

9. In combination a main burner, a pair of supplemental burners, a connecting 40 bracket at the rear of said main burner, said connecting bracket having passageways therein for connecting said main burner with said supplemental burner, and a valve mounted in said bracket, said valve controlling said passageways.

10. In combination a main burner, a pair of supplemental burners, a bracket at the rear of said main burner connecting said main burner with said supplemental burners, said bracket having passageways therein for connecting the main burner with the supplemental burners, valve means in said bracket for governing said passages, a housing for the front end of said burner, a vaporizer having a tube passing through said housing, said bracket having means for supporting said vaporizer, and a nozzle for said main burner, said nozzle being connected to said vaporizer and being contained with- 50 in said housing.

In witness whereof, I hereunto subscribe my name this 16th day of December, A. D. 1916.

PHILIP D. JOHNSON.
